UNITED STATES PATENT OFFICE.

GEORGE H. GILMAN, OF BOSTON, MASSACHUSETTS, ASSIGNOR TO SULLIVAN
MACHINERY COMPANY, A CORPORATION OF MASSACHUSETTS.

PRESSURE-FLUID MOTOR.

Application filed December 31, 1917, Serial No. 209,791. Renewed November 5, 1923.

To all whom it may concern:

Be it known that I, GEORGE H. GILMAN, a citizen of the United States, residing at Boston, in the county of Suffolk and State 5 of Massachusetts, have invented certain new and useful Improvements in Pressure-Fluid Motors, of which the following is a full, clear, and exact specification.

My invention relates to pressure fluid 10 motors.

It has for its object to provide an improved pressure fluid motor. A further object of my invention is to provide an improved pressure fluid motor which is especially adapted to use in a percussive tool, and which is of an improved construction adapted to increase materially the cutting speed of the tool and at the same time eliminate all difficulty with the piston striking 20 the heads of the cylinder or with sticking of the piston within the cylinder. A still further object of my invention is to provide an improved motor of the valveless type wherein at the same time that operation of 25 the motor is improved, the construction is simplified in such a manner that the same may be manufactured at small expense. Other objects and advantages of my improved construction will, however, herein- 30 after more fully appear.

In order that my invention may be disclosed, I have shown for purposes of illustration in the accompanying drawings, one embodiment which my invention may assume in practice.

In these drawings,—

Fig. 1 is a longitudinal sectional view of a percussive tool equipped with my improvement, the section being taken on line 1—1 40 of Fig. 3, and the piston being shown in one extreme position.

Fig. 2 is a similar sectional view taken on line 2—2 of Fig. 4, the piston being shown in its other extreme position.

Fig. 3 is a transverse sectional view taken on line 3—3 of Fig. 1.

Fig. 4 is a transverse sectional view taken on line 4—4 of Fig. 2.

In this illustrative construction, it will be 50 observed that I have shown a motor cylinder 1 having therein a piston comprising a short front head 2 and a preferably longer rear head 3. As shown, these heads 2 and 3 are spaced apart by a reduced portion 4, and 55 are of equal diameter and provided, respec-

tively, with front and rear pressure surfaces 5 and 6 of different area, the rear area 6 being materially larger than the front area 5. As in a usual construction, this piston operates between the rear cylinder head 7 60 and the front cylinder head 8, and is also provided on its front end with a forwardly extending reduced hammer portion 9 reciprocable through the front head into engagement with the rear end of a tool 10 carried 65 in a suitable chuck. It will also be observed that, as usual, pressure fluid is supplied to the rear head 7 through a supply pipe 12 under the control of a valve 13, and that the front and rear heads are connected by the 70 usual side rods 14, preferably resiliently mounted, as shown at 15.

In the construction shown, the pressure fluid supply is conducted through suitable 75 passages (not shown) from the supply pipe 12 to a plurality of longitudinally disposed inlet passages 16 disposed within the cylinder wall and at opposite sides of the rear end of the cylinder. As shown, each of these inlet passages 16 is also provided with 80 a lateral fluid pressure supply port 17 at its front end opening into the cylinder at a point intermediate its ends but preferably slightly nearer the rear end thereof. As illustrated, a longitudinally disposed port 18, 85 preferably of reduced diameter, is also provided in a suitable septum 19 at the front end of each of the inlet passages 16, which port 18 in turn communicates with a longitudinally disposed elongated reservoir or 90 pressure fluid storage chamber 20 forming an extension of the inlet passage and similarly disposed within the lines of the cylinder casing. Each of these chambers 20 is in turn provided at its rear end with a 95 lateral port 21, constituting a fluid pressure supply port for the cylinder and preferably of substantially the same size as the port 17, which is adapted to communicate with the cylinder, preferably at a point closely adjacent that port, the same herein being shown as opening into the cylinder on the opposite side of the septum 19. In the form of the invention here illustrated, a plurality 100 of cooperating longitudinally disposed passages 22 are also provided in the cylinder wall opposite the passages 16 and at the rear end of the cylinder. As shown, each of these passages 22 is also provided at its opposite ends with lateral ports 23 and 24 105 110

each communicating with the cylinder, of which ports the inlet port 23 is located slightly in rear of the port 17, while the port 24 is located at the extreme rear end of the cylinder. As shown, a plurality of co-operating longitudinally disposed passages 25 is also provided in the cylinder wall in the opposite end of the cylinder casing from the passage 22, the same herein being shown to be located in such a manner as to form a continuation of the passage 22 but to be separated therefrom by a suitable septum 26. In the form of my invention shown herein, each of these passages 25 is provided at its rear end with a plurality of lateral inlet ports communicating with the cylinder and herein shown to include a small port 27 closely adjacent the rear end of the passage 25 and an adjacent larger port 28. It will also be observed that each of the passages 25 is provided at its opposite end with another lateral port 29 communicating with the cylinder at a point adjacent the front end of the latter, and that this port 29 is in turn provided with a constantly communicating leakage port 30 leading to the extreme front end of the cylinder. As in a usual construction, it will of course be understood that exhaust ports 31 and 32 are also provided in the opposite ends of the cylinder in order to cooperate with the piston and to be controlled thereby in permitting the escape of exhaust pressure fluid from the cylinder.

In the operation of my improved construction illustrated, when pressure fluid is admitted to the inlet passage 16 with the piston in the position shown in Fig. 1, the pressure fluid will flow into the chambers 20 through the restricted openings 18 and through the port 17 into the space surrounding the reduced portion 4 of the piston. From this space it will be conducted by ports 23, passages 22, and ports 24 to the rear pressure surface 6 of the piston. As a result of the pressure acting upon this surface, the piston will move forward, i. e., to the right in Fig. 1, and cause the rear head 3 of the piston to close the ports 23. From this moment to the completion of the forward stroke, the piston will move under the influence of expansion of the motive fluid in the rear end of the cylinder. From the instant when ports 23 are closed to the instant when ports 27 are opened by the front head of the piston, the only possible place to which air may flow from the inlet will be through ports 18, and also from ports 17 through ports 21 by way of the groove in the piston, into the storage chambers 20. These chambers will accordingly be filled with fluid substantially at inlet pressure. When the ports 27 are opened, there will be a momentary rush of live fluid across the groove in the piston from ports 17 and through ports 27 into passages 25. A very slight movement of the piston will, however, close ports 17 and thereafter all the pressure fluid conducted to the front end of the cylinder, other than that already stored in chambers 20, must pass through ports 18. As the piston moves forward, there will be an expansion of the pressure fluid in chamber 20 through ports 27 and 28, passages 25 and ports 29 into the front end of the cylinder and the cushioning action of this pressure will be somewhat reduced by the fact that the pressure so acting is only the fluid expanding out of chambers 20, supplemented by the volume which can flow through the restricted passages 18, rather than live fluid flowing directly from live fluid ports equivalent in area to ports 21. Should the piston move far enough forward, as may occur with the ports 21 located as shown, the pressure fluid within the groove of the piston, in passages 25, and in the front end of the cylinder will be cut off from communication with the supply and somewhat compressed as the movement of the piston continues after ports 21 have been overrun, but the work of the compression of this fluid will be returned to the piston upon the rearward stroke. It should be understood, as indicated in Fig. 2, that the ports 21 is closed only at, or after, the moment of impact, and accordingly this compressive action will occur to a much less degree in drilling than will be the case in the event that the motor is being run idly, i. e., without a steel in the chuck. In fact, it will be obvious that due to the usual variation in the shank length of hand sharpened steels as turned out by the ordinary mine smith, the ports 21 will be caused to be closed by a small margin, to close line and line, or even to be slightly open at the moment of impact. Upon the return stroke of the piston, the ports 21 will again be opened and as the volume in the front end of the cylinder increases, the pressure fluid in the storage chambers 20 will continue to expand around through passages 25 to act on the front end of the piston. This fluid from the storage chambers 20 will be supplemented by live fluid entering through the ports 18, but it will be understood that the size of these ports being relatively small the rate of flow through the ports 18 may be insufficient to maintain the pressure in the front end of the cylinder as high as the pressure in the passage 16 and so that a partial expansion may occur in the front end of the cylinder prior to the closing of the ports 27. This, however, will depend on the flow areas of the ports 18, which, as indicated above, may be varied to suit different purposes. Just at the moment of closure of these ports, there will be another momentary supply of fluid directly across from ports 130

17. After the closure of ports 27, the storage chambers 20 will be charged with fluid up to full pressure and upon opening of ports 23, fluid will again pass to the rear end of the cylinder to cushion the piston and again cause its forward stroke. During the latter half of the forward stroke the rate of flow of fluid from storage chambers 20 to the front end of the cylinder is less than 5 would be the case were the ports 18 of a size equal to that of passages 16. Since the passages 18 are of a reduced area, they are unable to supply fluid to the forward end of the cylinder at as great a rate as would 10 be the case were fluid to flow directly from the inlet passages 16 to the ports 21 without restricted bores between these points. It will be understood that the piston is moving with maximum velocity at the moment when 15 the ports 27 are brought in communication with ports 21 and that during the exceedingly minute fraction of a second between this moment and the moment when the stroke is completed, but little more fluid can 20 flow into the chambers 20 through ports 18 and accordingly a less degree of cushion pressure will result than would be the case were the passages 18 larger. During the interval when the piston is at the front end of 25 the cylinder and reversing its travel, the pressure in chambers 20 may be materially raised. During the rearward stroke, the pressure transmitted to the front end of the piston will accordingly be somewhat higher, 30 but owing to the small size of the ports 18, the pressure may again begin to fall off somewhat prior to the closing of the ports 27 and from the moment when the ports 27 are closed until the piston reaches the 35 rear end of its stroke, the action will be entirely expansive. It should be understood that the ports 27 are of such small size as to constitute starting and cushion ports rather than main fluid ports and that their 40 effect, when the motor is operated at full speed, will be relatively small both from the standpoint of pre-admission and also from the standpoint of the supply of fluid direct from ports 17 during the return stroke. 45 The ports 18 are so designed, as a result of tests, that the drilling speed is a maximum in proportion to air consumption, that area being used where the best offset is found between high cushion resulting from pre-admission and lack of fluid in sufficient quantity to effect a satisfactorily rapid return stroke.

In the use of my improved motor in connection with a precessive drill, it has been found that not only the power of the blow, but the number of blows obtainable in a given time, has been materially increased in such a manner as phenomenally to increase the drilling speed. It has also been found 50 that, even although live air is admitted to

the piston at different times in its operation, the air consumption is thereby only increased to such a minor degree as to be insignificant when the increased drilling speed is considered. It has also been demonstrated 55 that through the utilization of my improved construction including the chamber 20, it has been possible to provide an additional supply of air which acts effectively to increase the speed of the piston on its rearward stroke without in any way reducing the effective pressure in the inlet. Through the provision of my improved port arrangements including the connections to the live air supply and the chamber 20, it has also 60 been found that a proper degree of cushion is provided for the front end of the piston under all conditions of operation and that through the provision of my improved connections controlling the supply of fluid to 65 the rear end of the piston, an effective cushion is produced tending to cushion the piston in its rearward stroke. Through the provision of my improved construction including the port 30, it has also been found 70 that any difficulty with the sticking of the piston within the cylinder at the forward limit of its movement is also effectually overcome. These and other advantages of my 75 improved construction will, however, be clearly apparent to those skilled in the art.

While I have in this application specifically described one embodiment which my invention may assume in practice, it will be understood that this form of the same is 80 used for purposes of illustration, and that the invention may be modified and embodied in other forms without departing from its spirit or the scope of the appended 85 claims.

What I claim as new and desire to secure by Letters Patent is:

1. In a pressure fluid motor, a cylinder, a piston therein, and means for effecting reciprocation of said piston including a plurality of fluid pressure supply ports having direct communication with a source of pressure through passages of different flow areas, and means for connecting said supply ports with the ends of the cylinder. 100

2. In a pressure fluid motor, a cylinder, a piston therein, and means for effecting reciprocation of said piston including a plurality of fluid pressure supply ports having direct communication with a source of pressure through passages of different flow areas, and means for connecting each of said supply ports with one end of said cylinder. 110

3. In a pressure fluid motor, a cylinder, a piston therein, and means for effecting reciprocation of said piston including a plurality of fluid pressure supply ports having direct communication with a source of pressure through passages of different flow areas, and means for admitting live air to 120

130

- areas, and means for alternately connecting each of said supply ports with both ends of said cylinder.
4. In a pressure fluid motor, a cylinder, a piston therein, and means for effecting reciprocation of said piston including a plurality of longitudinally spaced fluid pressure supply ports, one of which is provided with a supply passage adapted to communicate directly with the source of fluid pressure and the other of which is connected with said supply passage by a passage of less flow area than said supply passage, and means for connecting said supply ports with the ends of the cylinder.
5. A valveless fluid pressure percussive motor comprising a cylinder, a piston therein having heads of equal diameter separated by a reduced portion to form a groove, a pair of longitudinally separated fluid supply ports, and a pair of longitudinally separated fluid distribution passages communicating with the bore of said cylinder at the opposite ends thereof and also by ports at points between the most adjacent edges of said fluid supply ports and the ends of said cylinder.
6. A valveless fluid pressure percussive motor comprising a cylinder, a piston therein having heads of equal diameter separated by a reduced portion forming a groove, a pair of longitudinally separated fluid supply ports, and a pair of longitudinally separated fluid distribution passages communicating with the bore of said cylinder at the opposite ends thereof and also by ports at points between the most adjacent edges of said fluid supply ports and the ends of said cylinder, one of said passages communicating with said cylinder bore also by a port intermediate one of said last mentioned ports and the end of the cylinder.
7. A valveless fluid pressure percussive motor comprising a cylinder, a piston therein having heads of equal diameter separated by a reduced portion forming a groove, a pair of longitudinally separated fluid supply ports, and a pair of longitudinally separated fluid distribution passages communicating with the bore of said cylinder at the opposite ends thereof and also by ports at points between the most adjacent edges of said fluid supply ports and the ends of said cylinder, both of said passages being connectible by said piston groove with both of said fluid pressure supply ports.
8. In a valveless pressure fluid motor, a cylinder, a piston therein having a peripheral groove, and means for effecting reciprocation of said piston including a pair of longitudinally spaced lateral fluid pressure supply ports provided with means for direct connection to a source of fluid pressure supply, and means for alternately connecting both of said ports to each end of said cylinder comprising distribution passages adapted to cooperate with the peripheral groove in said piston.
9. In a pressure fluid motor, a cylinder, a piston therein having a peripheral groove, and means for effecting reciprocation of said piston including a pair of longitudinally spaced lateral fluid pressure supply ports provided with means for direct connection to a source of fluid pressure supply, and bypass passages leading to the ends of said cylinder and connectible with said supply ports by said peripheral groove, both of said ports being immediately connectible with each of said bypass passages upon initial admission to the latter through said groove.
10. In a pressure fluid motor, a cylinder, a piston therein having a plurality of heads, and means for reciprocating said piston including a plurality of lateral fluid pressure supply ports each of which is successively opened and closed by one of said heads and one of which is successively opened and closed by the other head and cooperating passages for delivering fluid from said supply ports to the opposite ends of said cylinder.
11. In a pressure fluid motor, a cylinder, a piston therein having a plurality of heads, and means for reciprocating said piston including a plurality of lateral fluid pressure supply ports each of which is successively opened and closed by one of said heads and one of which is successively opened and closed by the other head and cooperating passages leading to the opposite ends of said cylinder and having their communication with said supply ports controlled by said first mentioned head.
12. In a pressure fluid motor, a cylinder, a piston therein having heads of equal diameter, and means for reciprocating said piston including a plurality of lateral fluid pressure supply ports controlled by said piston and communicating with one another through a passage of less flow area than the area of either of said ports, and means for conducting fluid from said supply ports to the ends of the cylinder.
13. In a pressure fluid motor, a cylinder, a piston therein having a plurality of heads spaced by an annular groove, and means for reciprocating said piston including a plurality of lateral fluid pressure supply ports directly connected during operation of the motor to a fluid pressure supply source and controlled by said piston, one of the same having a communicating fluid pressure storage chamber, and means including a plurality of passages for conducting fluid from said supply ports to the ends of the cylinder.
14. In a pressure fluid motor, a cylinder, a piston therein having a plurality of heads spaced apart by a peripheral groove, and

- means for reciprocating said piston including a plurality of passages communicating with the ends of the cylinder and a plurality of adjacent lateral fluid pressure supply ports, one having a communicating pressure fluid storage chamber communicating with the other and both of said ports being communicable with both of said distributing passages. 5
- 10 15. In a pressure fluid motor, a cylinder, a piston therein having heads of equal diameter, and means for reciprocating said piston including a pair of lateral fluid pressure supply ports one of which is opened by one of said heads as it moves in one direction and both of which are thereafter successively closed by the other head. 15
16. In a pressure fluid motor, a cylinder, a piston therein having a plurality of heads spaced by an annular groove, and means for reciprocating said piston including a pair of longitudinally spaced lateral fluid pressure supply ports controlled by said piston and cooperating passages connectible by said piston simultaneously with both of said pressure supply ports and operative to conduct fluid to the ends of said cylinder. 25
17. In a pressure fluid motor, a cylinder, a piston therein having a plurality of heads separated by an annular groove, and means for reciprocating said piston including a plurality of fluid pressure supply ports successively closed by one head of the piston and bypass passages leading to the ends of said cylinder, one of said bypass passages having a plurality of ports successively opened by the other piston head. 35
18. In a pressure fluid motor, a cylinder, a piston therein having heads of equal diameter, and means for reciprocating said piston including a plurality of lateral fluid pressure supply ports successively closed by one head of said piston, and bypass passages leading to the ends of the cylinder, one of said bypass passages having a plurality of ports of different size successively opened by the other piston head. 40
19. In a pressure fluid motor, a cylinder, a piston therein having heads of equal diameter, and means for reciprocating said piston including a plurality of lateral fluid pressure supply ports each of which is successively opened and closed by one of said heads and one of which is successively opened and closed by the other head and cooperating passages for delivering fluid from said supply ports to the opposite ends of said cylinder. 55
20. In a pressure fluid motor, a cylinder, a piston therein having heads of equal diameter, and means for reciprocating said piston including a plurality of lateral fluid pressure supply ports each of which is successively opened and closed by one of said heads and one of which is successively opened and closed by the other head and cooperating passages leading to the opposite ends of said cylinder. 60
- opened and closed by the other head and cooperating passages leading to the opposite ends of said cylinder and having their communication with said supply ports controlled by said first mentioned head. 70
21. In a pressure fluid motor, a cylinder, a piston therein having heads spaced by a peripheral groove, and means for reciprocating said piston in one direction including a pair of lateral fluid pressure supply ports controlled by said piston and both adapted to be closed thereby in one position thereof, and a plurality of cooperating distribution passages leading to the ends of the cylinder, one of said distribution passages having a plurality of ports successively opened by one of said heads prior to the closure of both of said supply ports. 75
22. In a pressure fluid motor, a cylinder, a piston therein having heads separated by an annular groove, and means for reciprocating said piston in one direction including a pair of lateral fluid pressure supply ports controlled by said piston and both adapted to be closed by one head thereof in one position thereof, and a plurality of cooperating ports of different size leading to one end of said cylinder and successively opened by the other of said heads prior to the closure of both said supply ports by the first mentioned head. 85
23. In a pressure fluid motor, a cylinder, a piston therein having heads spaced apart by an annular groove, and means for reciprocating said piston in one direction including a pair of communicating lateral fluid pressure supply ports successively closed by one head of the piston, and a plurality of cooperating ports of different size leading to the other end of the cylinder and successively opened in the order of their increasing size by the other of said heads prior to the closure of both of the supply ports by the first mentioned head. 90
24. In a pressure fluid motor, a cylinder, a piston therein having heads of equal diameter, and means for reciprocating said piston including a plurality of longitudinally spaced lateral fluid pressure supply ports one communicating with a source of pressure fluid supply and the other communicating through a pressure chamber with said source and cooperating passages leading to the opposite ends of said cylinder one having a port extending to the extreme end of said cylinder. 100
25. In a pressure fluid motor, a cylinder, a piston therein having heads of equal diameter, and means for reciprocating said piston including a plurality of longitudinally spaced lateral fluid pressure supply ports one communicating with a source of pressure fluid supply and the other communicating through a pressure chamber with said source, cooperating passages lead- 115
- 120
- 125
- 130

- ing to the opposite ends of said cylinder one having a port opening into said cylinder and adjacent one end of the same and a constantly communicating port extending to the extreme end of said cylinder, and means for connecting said cooperating passages with said fluid pressure supply ports.
26. In a pressure fluid motor, a cylinder, a piston therein having heads of equal diameter, and means for reciprocating said piston including a plurality of lateral fluid pressure supply ports each of which is successively opened and closed by one of said heads and one of which is successively opened and closed by the other head and cooperating passages leading to the opposite ends of said cylinder and having their communication with said supply ports successively closed and thereafter successively opened by said first mentioned head.
27. In a pressure fluid motor, a cylinder, a piston therein, and means for reciprocating said piston including a plurality of lateral fluid pressure supply ports, and cooperating passages leading to the opposite ends of said cylinder, one of said passages having an inlet port spaced longitudinally from said supply ports.
28. In a pressure fluid motor, a cylinder, a piston therein, and means for reciprocating said piston including a plurality of lateral fluid pressure supply ports, and cooperating passages leading to the opposite ends of said cylinder, said passages having inlet ports spaced longitudinally from said supply ports.
29. In a pressure fluid motor, a cylinder, a piston therein, and means for reciprocating said piston including a plurality of lateral fluid pressure supply ports, and cooperating passages leading to the opposite ends of said cylinder, one of said passages having a plurality of inlet ports spaced longitudinally from said supply ports.
30. In a pressure fluid motor, a cylinder, a piston therein, and means for reciprocating said piston including a plurality of lateral fluid pressure supply ports, and cooperating passages leading to the opposite ends of said cylinder, one of said passages having a plurality of inlet ports of different size spaced longitudinally from said supply ports.
31. In a fluid pressure percussive motor, a cylinder, a piston therein, and means for effecting reciprocation of said piston including a main fluid pressure supply port, an auxiliary pressure fluid supply port separated therefrom longitudinally of the cylinder, a restricted passage connecting said ports, and a bypass passage leading to one end of the cylinder cooperating with said auxiliary inlet port.
32. A fluid pressure motor comprising a cylinder, a piston therein, and fluid distribution means including distribution ports leading to the ends of the cylinder, and supply means for said distribution ports including a fluid pressure supply port provided with a supply passage having therein a restricted orifice.
33. A fluid pressure motor comprising a cylinder, a piston therein, and fluid distribution means including a fluid pressure supply port adapted to be brought into communication with one end of the cylinder, and passage means of less flow capacity than said supply port to connect it with a source of fluid supply.
34. A fluid pressure motor comprising a cylinder, a piston therein, and fluid distribution means including a fluid pressure supply port adapted to be brought alternately into communication with the opposite ends of the cylinder, and means of less flow capacity than said supply port to connect it with a source of fluid supply.
35. A fluid pressure motor comprising a cylinder, a piston therein, and means for effecting reciprocation of said piston including a fluid pressure storage chamber having a port adapted to be brought into communication with one end of the cylinder, and means for charging said storage chamber prior to said communication.
36. A fluid pressure motor comprising a cylinder, a piston therein, and means for effecting reciprocation of said piston including a fluid pressure storage chamber having a port adapted to be brought into communication with one end of the cylinder, and means for charging said storage chamber prior to and during said communication.
37. A fluid pressure motor comprising a cylinder, a piston therein, and means for effecting reciprocation of said piston including a fluid pressure storage chamber having a port adapted to be brought into communication with one end of the cylinder, and means for charging said storage chamber comprising means to connect said port with a fluid supply prior to the communication with the end of the cylinder.
38. A fluid pressure motor comprising a cylinder, a piston therein, and means for effecting reciprocation of said piston including a fluid pressure storage chamber having a port adapted to be brought into communication with one end of the cylinder, and means for charging said storage chamber comprising means formed in said piston to connect said port with a fluid supply prior to the communication with the end of the cylinder.
39. A fluid pressure motor comprising a cylinder, a piston therein, and means for effecting reciprocation of said piston including a fluid pressure storage chamber having a port adapted to be brought into communication with one end of the cylinder, and

means for charging said storage chamber comprising means to connect said port with a fluid supply during its communication with one end of the cylinder.

- 5 40. A fluid pressure motor comprising a cylinder, a piston therein, and means for effecting reciprocation of said piston including a fluid pressure storage chamber having a port adapted to be brought into communication with one end of the cylinder, and means for charging said storage chamber comprising means to connect said port with a fluid supply during its communication with the other end of said cylinder.
- 10 41. A fluid pressure percussive motor comprising a cylinder, a piston therein, and means for distributing fluid to effect reciprocation of said piston including fluid distribution ports leading to the opposite ends of said cylinder, fluid pressure supply means comprising an inlet port, and a storage chamber having a port adapted to be brought into communication with said inlet port and with one end of said cylinder in alternation.
- 15 42. A fluid pressure percussive motor comprising a cylinder, a piston therein, and means for distributing fluid to effect reciprocation of said piston including fluid distribution ports leading to the opposite ends of said cylinder, and fluid pressure supply means comprising an inlet port and a storage chamber communicable with an end of said cylinder when said inlet port is closed and having a port adapted to be brought into communication with one end of said cylinder and with said inlet port simultaneously.
- 20 43. A fluid pressure percussive motor comprising a cylinder, a piston therein, and means for distributing fluid to effect reciprocation of said piston including fluid distribution ports leading to the opposite ends of said cylinder, fluid pressure supply means comprising an inlet port and a storage chamber communicable with an end of said cylinder when said inlet port is closed, and means to conduct fluid pressure from said inlet port simultaneously to said storage chamber and to one end of said cylinder.
- 25 44. A fluid pressure percussive motor comprising a cylinder, a piston therein, and
- means for distributing fluid to effect reciprocation of said piston including fluid distribution ports leading to the opposite ends of said cylinder, fluid pressure supply means comprising an inlet port and a storage chamber communicable with an end of said cylinder when said inlet port is closed, and means to connect said inlet port with one end of said cylinder and said storage chamber with said end subsequent to the interruption of the communication of said inlet port.
- 30 45. A fluid pressure motor comprising a cylinder, a piston reciprocating therein, and means for distributing fluid to effect reciprocation of said piston including fluid distribution passages leading to the ends of said cylinder, and fluid supply means comprising a storage chamber communicable with an end of said cylinder when said inlet port is closed and adapted to be filled during one pass of said piston and to communicate with an end of said cylinder during the next succeeding pass.
- 35 46. A fluid pressure percussive motor comprising a cylinder, a piston therein, and means for distributing fluid to effect reciprocation of said piston including fluid distribution passages leading to the opposite ends of said cylinder, fluid pressure supply means comprising an inlet port and a storage chamber communicable with an end of said cylinder when said inlet port is closed, and means for connecting said storage chamber with said inlet port and subsequently with one of said distribution passages.
- 40 47. A fluid pressure percussive motor comprising a cylinder, a piston therein, and means for distributing fluid to effect reciprocation of said piston including fluid distribution passages leading to the opposite ends of said cylinder, fluid pressure supply means comprising an inlet port and a storage chamber communicable with an end of said cylinder when said inlet port is closed, and means for connecting said storage chamber with said inlet port and with one end of said cylinder, closing said last mentioned connection and reopening the same during a cycle for one end of said cylinder.
- 45 48. In testimony whereof I affix my signature.
GEORGE H. GILMAN.
